Primary Examiner—Paula A. Mortimer

(74) *Attorney, Agent, or Firm*—Knobbe, Martens, Olson & Bear, LLP

(57) **CLAIM**

The ornamental design for a ball cap with tassel [and removable button], as shown and described.

DESCRIPTION

FIG. 1 is a front isometric view of the ball cap with tassel of the present design;

FIG. 2 is a front view thereof;

FIG. 3 is a back view thereof;

FIG. 4 is a right-side view thereof;

FIG. 5 is a top view thereof;

FIG. 6 is a bottom view thereof; and,

FIG. 7 is a right-side view thereof, illustrating that a button can be removed from the cap.

*The broken lines disclose conventional stitching in all views.
The hatching discloses fabric in all views.*
